[57] CLAIM

The ornamental design for a blower assembly, as shown and described.

DESCRIPTION

FIG. 1 is a front perspective view of a blower assembly showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The strap shown in broken lines in FIG. 1 is for illustrative purposes only and forms no part of the claimed design.

FIG. 1

FIG. 4

FIG. 5

FIG. 6

FIG. 7
